DESIGN FOR A COMBINED BOWLING ALLEY BED AND APPROACH OR SIMILAR ARTI- CLE

Robert E. Kennedy, Chicago, Ill., assignor to The
Brunswick-Balke-Collender Company, Chicago,
Ill., a corporation of Delaware

Application January 25, 1943, Serial No. 109,343

Term of patent 14 years

To all whom it may concern:

Be it known that I, Robert E. Kennedy, a citizen of the United States, residing in the city of Chicago, county of Cook, State of Illinois, have invented a new, original, and ornamental Design for a Combined Bowling Alley Bed and Approach or Similar Article, of which the following is a specification, reference being had to the accompanying drawing forming a part thereof.

Fig. 1 is a plan view of a combined bowling alley bed and approach or similar article embodying my new design;

Fig. 2 is an enlarged fragmentary plan view of the portion of the bowling alley bed indicated by the bracket 2 in Fig. 1;

Fig. 3 is an enlarged fragmentary plan view of the portion of the bowling alley bed indicated by the bracket 3 in Fig. 1;

Fig. 4 is an enlarged fragmentary plan view of the portion of the bowling alley bed and approach indicated by the bracket 4 in Fig. 1;

Fig. 5 is an enlarged fragmentary plan view of the portion of the bowling alley approach indicated by the bracket 5 in Fig. 1;

Fig. 6 is an elevational view looking at the right-hand end of Fig. 1.

The dominant features of the design are shown in full lines.

This application is a continuation, in part, of my application Serial D-107,275 filed June 20, 1941.

I claim—

The ornamental design for a combined bowling alley bed and approach or similar article, as shown and described.

ROBERT E. KENNEDY.
